United States Patent Office

Des. 212,111

Patented Aug. 27, 1968

212,111

CUP HOLDER

Melvin Zaretsky, 1408-A O St.,
Sacramento, Calif. 95814

Filed May 5, 1967, Ser. No. 6,958

Term of patent 14 years

(Cl. D44—10)

I claim:

The ornamental design for a cup holder, substantially as shown.
